UNITED STATES PATENT OFFICE.

GEORGE H. TABER, OF BINGHAMTON, NEW YORK, ASSIGNOR TO EMC CO MANUFACTURING COMPANY, INC., OF BINGHAMTON, NEW YORK, A CORPORATION OF NEW YORK.

HAND-OPERATING DEVICE FOR MUFFLER CUT-OUTS.

1,340,802.

Specification of Letters Patent.

Patented May 18, 1920.

Application filed October 17, 1919. Serial No. 331,504.

To all whom it may concern:

Be it known that I, GEORGE H. TABER, a citizen of the United States of America, and a resident of Binghamton, in the county 5 of Broome and State of New York, have invented certain new and useful Improvements in Hand-Operating Devices for Muffler Cut-Outs, of which the following is a specification.

10 This invention relates to improvements in hand operating devices adapted particularly for use in connection with a cut-out for an automobile, etc., and the object of the invention is to provide a simple hand operating 15 device which can be very easily manipulated and which cannot possibly get out of order. In the preferred embodiment, the invention consists of two main parts one of which is a support having a flaring or bell shaped 20 lower end to act as a substitute for a pulley, and the other a handle by which the chain connecting with the muffler cut-out may be pulled against the tension of the spring and secured so as to hold the cut-out in the open 25 position. The invention therefore consists in the peculiar construction and arrangement of parts hereinafter more particularly described and then definitely claimed.

In the drawings accompanying and forming part hereof:

Figure 1 is a view of part of an automobile showing a muffler under the floor of the car with my invention in position for use.

Fig. 2 is a perspective view of my hand 35 operating device detached.

Fig. 3 is a sectional view of my hand operating device in position for use, with the parts in position in which the cut-out is held open.

40 Referring now to the details of the drawings by numerals: 1 represents a muffler now in use having a cut-out valve 2 normally held against its seat by a spring 3. A chain 4 connects the valve 2 with the hand operating device so that when the chain 4 is drawn taut, the valve 2 of the cut-out will be open. When the chain 4 is released, a spring 6 acts upon the valve 2 to close the same in a manner well understood. The 45

50 parts of the cut-out muffler are well known and need no description and my present invention has no relation thereto except to show some means of drawing the chain 4 taut against the tension of the spring, and

of releasing the same so that the spring can 55 perform its function.

My hand operating device consists of two main parts 8 and 10. The part 8 is substantially flat and is preferably provided with three screw holes through which screws 60 may be inserted to secure the member 8 in the position shown in Figs. 1 and 3. This part 8 is really a support and has a flared or bell shaped lower end 12 through which the chain 4 passes, as clearly indicated in 65 Fig. 3, so that the flared end 12 acts as a substitute for a pulley. The part 8 is closed at the front end of the flared or bell shaped part 12, and above said part 12 said member 8 is provided with flanges 14 and 16 which 70 extend almost to the top of the support. A lug or hanger 18 is preferably cast integrally with the upper end of the support 8 and with this lug or hanger is adapted to coact a handle 20 preferably formed of the 75 shape shown in perspective view in Fig. 2. In other words, it is substantially T-shape and to the stem of the T is connected the chain 4 hereinbefore referred to. The upper part of the T forms two handles 22 and 24 80 of just the proper shape to be grasped by the fingers so that the handle may be drawn upwardly when it is desired to open the cut-out. Immediately under the parts 22 and 24 the T-shaped member is provided with an 85 opening 26 which is adapted, when the T-shaped member 10 is moved upwardly, to fit over the lug or hanger 18, as clearly shown in Figs. 2 and 3. When in this position the shank of the T is entirely out of the 90 bell shaped lower end 12 of the hanger. However, when the operator desires to release the T-shaped member all that he has to do is to slip it off of the lug or hanger 18 and the spring 6 hereinbefore referred to 95 will draw the chain so as to pull thereon to bring the stem of the T down through the bell shaped end 12 in the position clearly shown in Fig. 1. As a matter of fact, the 100 T-shaped handle when released from the lug or hanger 18 would drop by gravity into the position shown in Fig. 1 even if it were not drawn therein by the spring pulling upon the chain 4, but of course the action of the chain draws the lower end of the shank 105 of the handle into the bell shaped lower end as will be evident from the drawings. When the device is placed in position, it is only

necessary to secure the supporting member 8 in the position shown in Figs. 1 and 3, which can be very easily done, and inasmuch as the bell shaped member takes the 5 place of the pulley, its lower end is preferably arranged to extend to just the bottom of the flooring so that all wear will be taken by the casting and the floor thus relieved of any wear.

10 My invention is so simple that no further description of its operation is necessary.

From the foregoing and accompanying drawings, it will be seen that I have provided a hand operating device which consists of two main parts very simple in construction, quick in operation and yet so durable that it will be almost impossible to get out of order.

What I claim as my invention is:

- 20 1. As a new article of manufacture, a hand operating device for muffler cut-outs comprising a hanger substantially flat whereby it may be easily secured in position and having a bell-shaped lower end 25 and a lug or hanger near its upper end, and a handle adapted to be hung upon said lug or hanger and provided with a chain passing through said bell shaped end, substantially as described.
- 30 2. As a new article of manufacture, a hand operating device for muffler cut-outs comprising a hanger substantially flat whereby it may be easily secured in position and having a bell shaped lower end 35 and a lug or hanger near its upper end, and a T-shaped handle adapted to be hung upon said lug or hanger and provided with a chain passing through said bell shaped end, the T-shaped handle shaped so as to be

grasped by the fingers of the user, substantially as described.

3. As a new article of manufacture, a hand operating device for muffler cut-outs comprising a hanger substantially flat whereby it may be easily secured in position and having a bell shaped lower end and a lug or hanger near its upper end, and a T-shaped handle adapted to be hung upon said lug or hanger and provided with a chain passing through said bell shaped end, 50 the shank of the T-shaped handle being adapted to enter the bell shaped lower end and the upper end of said handle being shaped to be grasped by the fingers of the user, substantially as described. 55

4. As a new article of manufacture, a hand operating device for muffler cut-outs comprising a hanger substantially flat whereby it may be easily secured in position and having a bell shaped lower end 60 and a lug or hanger near its upper end, and a T-shaped handle adapted to be hung upon said lug or hanger and provided with a chain passing through said bell shaped end, the shank of the T-shaped handle being 65 arranged to drop through the bell shaped end, with the head of the T resting on the upper part of said bell shaped end, and said T-shaped handle being shaped so that it may be easily grasped by the fingers of 70 the user and elevated and hung upon said lug or hanger, substantially as described.

In testimony whereof I affix my signature in presence of two witnesses.

GEORGE H. TABER.
